UNITED STATES PATENT OFFICE.

CHARLES M. GARST, OF INDEPENDENCE, MISSOURI.

PAINT-BUCKET HANGER.

1,339,025.

Specification of Letters Patent.

Patented May 4, 1920.

Application filed June 28, 1918. Serial No. 242,486.

To all whom it may concern:

Be it known that I, CHARLES M. GARST, a citizen of the United States, residing at Independence, in the county of Jackson, State 5 of Missouri, have invented certain new and useful Improvements in Paint-Bucket Hangers; and I do hereby declare the following to be a full, clear, and exact description of the invention, such as will enable others 10 skilled in the art to which it appertains to make and use the same.

This invention relates to improvements in ladder attachments and particularly to attachments for supporting paint buckets, 15 brushes, or other tools.

One object of the present invention is to provide a novel and improved device of this character wherein the hanger for the bucket and tools is capable of quick and easy adjustment to permit the bucket and tools to 20 be supported in perpendicular positions.

Another object is to provide a novel and improved structure of this character wherein the support for the articles can be firmly 25 but detachably connected to the side rail of the ladder, and at the point most convenient for the workman.

Other objects and advantages will be apparent from the following description when 30 taken in connection with the accompanying drawing.

In the drawing:

Figure 1 is a front elevation of the invention applied to a ladder.

Fig. 2 is a side elevation of the same.

Fig. 3 is an enlarged vertical sectional view taken on the line 3—3 of Fig. 2.

Fig. 4 is a top plan view of the device.

Fig. 5 is an enlarged fragmentary sectional view taken on the line 5—5 of Fig. 3.

Referring particularly to the accompanying drawing, 10 represents a disk to the center of one face of which there is secured a hollow cylindrical member 11, said disk having a central opening 12 registering with the adjacent end of the member 11. Near the periphery of the disk there is formed the circular series of openings 13. Disposed through the member 11 is a member 14, and secured to the outer end of the member 14 15 is a disk 15, said disk having a plurality of openings 16, and 17 formed adjacent the periphery thereof, the latter of which are adapted to register with two of the openings 55 of the disk 10. Slidably disposed in

the opening 16 is the central leg 19 of the detent member 20. This member 20 is formed with two other legs 21 which are arranged to pass through the openings 17 and certain of the openings 13 of the disk 10. 60 Connected to the member 20 and to the disk 15 is a coil spring which normally exerts a pull on the member 20 to engage the legs 21 through the said openings. By pulling outwardly on the member 20 the legs 21 can be 65 disengaged from the openings 13 to permit the rotation of the disk 15 relatively to the disk 10.

The member 14 is disposed longitudinally through the member 11 and the inner end thereof is provided with threads for engagement of a nut 23 thereon. The outer end 14' of the member 14, which projects a suitable distance beyond the outer face of the disk 15, is formed with an upturned portion 24 70 75 on which is centrally pivoted a horizontally disposed circular platform 25. Secured at four or more points on the periphery of the platform 25 are the uprights 26, and connecting the upper ends of these uprights is 80 a ring 27. On this frame, and between the uprights, a paint pot or bucket may be placed. On the outer portion of each of the uprights, or certain ones, as desired, are the paint brush or tool holding clips 28. On 85 one side of the member 14 there is formed a socket portion 29 in which a hammer or other like tool may be inserted to be supported within convenient reach of the workman. 90

Detachably connected to the other face of the disk 10 are the pair of arms 30, each being formed with a recess 31 for the reception of a portion of the side rail of the ladder. In the outer ends of these arms 95 there are formed openings 32 which receive therethrough the clamping bolts 33, a similar bolt 34 being disposed through openings 35 in the recessed portions of the arms, whereby the said arms are held firmly engaged with the rail of the ladder. 100

What is claimed is:

An attachment for a ladder including a ladder rail clamping means, a vertically disposed stationary disk carried by the clamping means and having openings therethrough adjacent the periphery and a hollow member extending from one face thereof, a member rotatably disposed through the disk and the hollow member and having a 110

disk thereon engaging one of its flat faces with the adjacent face of the first disk, a tool supporting means on the rotatable disk and movable therewith, said rotatable disk having openings for successive registry with the openings of the stationary disk, and a spring held yoke member having its arms engaged through the registered open-

ings and its intermediate portion slidably engaged with the rotatable disk.

In testimony whereof, I affix my signature, in the presence of two witnesses.

CHARLES M. GARST.
